UNITED STATES PATENT OFFICE

2,053,753

SURGICAL TRACTION FRAME

Frank O. Wellington, New London, Conn.

Application May 22, 1935, Serial No. 22,912

1 Claim. (Cl. 248—226)

The invention relates to a new and improved surgical apparatus for use in the reduction and treatment of fractures, the nature of the invention being similar to the so-called Balkan frame.

It has for years been the practice of surgeons in treating fractures to erect a frame structure of wood over the patient's bed, from which to suspend the required sheave blocks for pull lines leading from the fractured member or members to the weight or weights for extension and tension. These improvised rigs have been unsatisfactory due largely to the difficulty of properly locating and maintaining the desired points of suspension for the blocks.

My invention aims to provide a new and improved surgical traction apparatus in which this difficulty is overcome, and with this object in view, the invention resides in the novel subject matter hereinafter described and claimed, description being accomplished by reference to the accompanying drawings.

Figures 1 and 2 are perspective views showing the general relation of parts.

Figure 3 is a perspective view of one of the turntables 37 and associated structural features.

Figure 4 is a vertical sectional view through the turntable and associated elements shown in Fig. 3.

A preferred construction has been illustrated and will be rather specifically described, with the understanding however, that within the scope of the invention as claimed, variations may be made.

The entire frame structure which is adjustable to fit beds of different lengths and widths, is constructed from metal tubing or other appropriate metal frame members, and metal clamping means for securing the frame members together. I prefer to use transversely square tubing for all of the posts, rails, sheave-supporting arms, etc., and clamping means employed in connection with these parts are of such construction as to engage all four sides thereof to insure tenacious holding.

I provide four corner posts 20 for disposition at the four corners of the usual hospital bed B, said posts being of a height to project to the desired distance above the bed. These posts are provided with supporting casters 21 and with inwardly projecting brackets 22 upon which to rest the usual corner posts 23 of the bed B. Preferably each bracket 22 is of shelf-like form and is integral with a square frame 24, said frame surrounding the lower end of its respec-

tive posts 20 and being welded, riveted or otherwise secured thereto.

Longitudinal and transverse bounding rails 25 and 26 are provided, the end portions of these rails being secured by novel clamps 27 to the lower portions of the posts 20 for holding said lower portions of the posts in fixed relation with the bed. Similar longitudinal and transverse rails 28 and 29 are connected by clamps 30 with the upper ends of the corner posts 20 to hold 10 said ends in fixed relation with the bed. The rails 28 may well support any desired number of suspension rails, for instance, one rail 31 for a sheave block 32 and another rail 33 for a trapeze 34, each of these suspension rails being 15 adjustably secured to the rails 28 by novel clamps 35.

Sheave-supporting arms 36 are adjustably carried by turntables 37 and clamps 38 are provided for connecting any desired number of these 20 turntables with the corner posts 20. In the present showing, one of the arms 36 carries a twin sheave block 39 and another carries a single sheave block 40, both blocks being adjustably connected with the arms as hereinafter explained.

Elongated clamps 41 are provided, the ends of these clamps being adapted to engage and hold pull straps 42 for horizontally pulling a patient's injured limb or limbs. Connected with one of the clamps 41, centrally between the ends of said clamps, is a pull cable 43 which is trained over the pulley 40 and is connected with a weight holder 44 carrying one or more weights 45. Connected to another of the clamps 41, is a sheave 35 block 46 which is pivoted to said clamp as shown at 47.

A clamp 48 has been illustrated to engage the ends of a sling 49, or possibly pull straps. One end of a pull cable 50 is connected with the clamp 48 by a bridle or the like 51. This cable passes upwardly and over the sheave of the block 32, extends downwardly and around the upper sheave of the twin block 39, extends horizontally and around the sheave of the block 46, extends again 45 horizontally and over the lower sheave of the block 39, extends downwardly from the latter and is connected with a weight holder 44' which is identical with the holder 44, said holder 44' being provided with any desired number of weights 50 45'.

For supporting the sheave block 32, a suitable contractable collar 79 is adjustably carried by the suspension rail 31, being provided with a thumb nut 80 and associated stud for contracting it and 55

holding it in adjusted position. Collar 79 is provided with an eye 81 for suspending the sheave 32, said eye being preferably swiveled.

Two suitable collars 82 may surround the suspension rail 33 to support the trapeze 34.

The clamp 38 which mounts the turntable 37 upon the corner post 20, is preferably of the construction shown more clearly in Figs. 3 and 4, being provided with wing nuts 83 for applying and releasing it. This clamp, in the present showing is rigid with a transversely split ring 84 which surrounds the turntable 37 and may be contracted to non-rotatably hold said turntable, by means of a suitable clamping screw 85. The turntable 10 preferably comprises top and bottom plates 86 and 87, and a cylindrical side wall 88, the parts 15 86 and 88 being preferably integral with each other. Both plates 86 and 87 engage the edges of the ring 84 to prevent vertical movement of the 20 turntable with respect to said ring 84.

The top plate 86 is provided with two channel-shaped seats 89 for the arm 36 and is formed with an opening 90 between said seats. A clamping yoke 91 surrounds the arm 36 between the seats 25 89 and is provided with a shank 92 which passes downwardly through the opening 90 and through an opening in the bottom plate 87, being provided at its lower end with a thumb nut 93. After sliding of the arm 36 to the desired position, it may 30 be held in said position by tightening the nut 93. After swinging the arm 36 to any desired advantageous position, it may be held by tightening the screw 85. Thus, the sheave 39 or 49 or any other accessory or the like carried by the arm 36 may 35 be adjusted to the most advantageous position.

For connecting the sheave 40 with the arm 36, a collar 79' identical with the collar 79 may well be employed. For connecting the double sheave block

39 with the arm, a contractable collar 94 and a clevis 95 are employed, said clevis being pivoted on a vertical axis 96 to said collar 94 and being pivoted on a horizontal axis 97 to the central portion of the sheave block 39. This connection between 5 the sheave block and the collar permits any requisite movement of said sheave block without throwing the pull cable 50 out of proper relation therewith.

It will be seen from the foregoing that novel provision has been made for attaining the desired end. While a preferred construction has been illustrated, attention is again invited to the possibility of making numerous variations within the 10 scope of the invention as claimed. 15

I claim:

In a surgical traction frame, a split ring having a post-engaging clamp projecting horizontally therefrom for rigidly supporting the ring, a turntable comprising a side wall surrounded by said 20 ring, a top plate integral with said side wall and lying upon the upper edge of said ring, and a bottom plate separate from said side wall and lying against the lower edge of said ring, said top and bottom plates each having a central opening, 25 said top plate being provided with two upwardly facing seats at opposite sides of its central opening, an arm lying upon said seats, a bolt passing through the central openings of said top and bottom plates and having an eye surrounding said arm, a nut threaded upon the lower end of said bolt and abutting said bottom plate to hold said top and bottom plates engaged with the edges of said split ring and to hold said arm engaged with said seats, and means for contracting said split 30 ring to hold the turntable normally against rotation.

FRANK O. WELLINGTON.
